UNITED STATES PATENT OFFICE.

EUGENE M. SCOVILLE, OF MILWAUKEE, WISCONSIN, ASSIGNOR OF ONE-HALF TO
FLOYD L. SWANBERG, OF DANVILLE, ILLINOIS.

OIL PUMP.

Application filed September 22, 1922. Serial No. 589,748.

This invention relates in general to improvements in the art of lubrication, and relates more specifically to improvements in the construction and operation of oil pumps and similar apparatus.

An object of the invention is to provide an improved oil pump which is relatively simple and compact in construction, and highly efficient in operation.

10 Some of the more specific objects and advantages of the present invention, are as follows:—

To provide a relatively simple, durable and inexpensive oil pump which is effectively operable throughout a wide range of variation in capacity.

15 To provide an oil pump structure the elements of which are conveniently accessible for inspection, and various parts of which are readily adjustable to meet different conditions of operation.

To provide pump mechanism which may be readily manufactured, assembled and dismantled.

20 25 To generally simplify the construction of oil pumps with a view to reducing to a minimum the cost of manufacture and maintenance of such devices.

To provide mechanism which is capable 30 of efficiently handling various fluent substances, including lubricants which prior oil pumps have been unable to operate upon with commercial success.

35 To provide improved simple and efficient driving mechanism for oil pumps and the like.

40 To provide lubricating apparatus which may be operated either manually or automatically, and either intermittently or continuously.

To provide an extremely compact pump unit which may be readily assembled in nests of two or more units operable by means of a common drive mechanism and adapted 45 to receive fluid from a common supply reservoir.

50 To provide for rapid removal and replacement of any one or more pump units comprising a group, without interfering with the normal operation of other units of the group.

To provide improvements in the construction, disposition and operation of oil pump valve mechanism.

55 To eliminate undesirable leakage and

waste of oil in lubricating pumps and other apparatus.

To provide other improvements in the construction and operation of oil pumps which will reduce to a minimum the cost 60 of construction and which will enhance to a maximum the efficiency of operation.

Some of the novel features of oil pump construction disclosed but not specifically claimed herein, form the subject of copending application Serial Number 567,064, filed 65 June 9, 1922.

A clear conception of an embodiment of the various features of the present invention, and of the operation of devices constructed in accordance therewith, may be had by referring to the drawings accompanying and forming part of this specification, in which like reference characters designate the same or similar parts in the 70 several views.

Fig. 1 is a vertical section through an improved oil pump unit and the oil supply reservoir thereof, showing also a fragment 75 of the pump driving mechanism.

Fig. 2 is a longitudinal vertical section through the oil supply reservoir and the pump actuating mechanism, showing the manner of mounting several similar oil pumps relatively to the supply reservoir and actuating mechanism, the sections through the several pumps being taken in different vertical planes.

Fig. 3 is a top view of a group of oil 80 pumps units and of the supply reservoir and actuating mechanism therefor, part of the pump structure having been broken away and other pump elements having been removed in order to more clearly illustrate various details of construction.

Fig. 4 is a fragmentary vertical section 85 through the high pressure portion of one of the pump units.

Fig. 5 is a fragmentary vertical sectional view of a portion of the pump actuating 100 mechanism.

Fig. 6 is a fragmentary top view of a portion of the pump actuating mechanism.

Fig. 7 is a top view of the plungers and of the plunger connection of one of the 105 pump units.

The lubricant force feed apparatus illustrated in the drawings comprises generally a stationary casing 2 and a removable cover 22 cooperating therewith to provide an en- 110

closed oil supply reservoir of suitable capacity; pump actuating or driving mechanism located adjacent to the lower portion of the casing 2; a plurality of similar but 5 independent compound pumping units supported by the cover 22 and casing 2 and operatively associated with the common driving mechanism at the lower portion of the casing 2; and a plurality of independent 10 oil discharge pipes 6 rigidly attached to the casing 2 and capable of receiving oil from the pump units and of delivering the oil under pressure to sources of utilization.

The lower portion of the stationary casing 2 is provided with a heater 13 wherein 15 suitable heating agency may be utilized in order to maintain the oil 31 within the supply reservoir in proper fluent condition. One corner of the casing 2 may also be provided with an oil gage 55 for indicating 20 the quantity of oil within the supply reservoir. The oil 31 which may completely or only partially fill the supply reservoir, may be drained from the casing 2 by removal of 25 the plug 70. Oil is supplied to the interior of the casing 2 in any convenient manner through a filter 60 mounted upon the casing cover 22. The casing cover 22 is preferably 30 formed of sheet metal of suitable thickness, being clamped to the casing 2 and serving as a means of direct support for the pump units and for the filter 60. The sheet metal cover 22 is formed with a continuous upwardly projecting ridge 23 surrounding 35 each of the pump openings, and also has a similar ridge 69 surrounding the filter 60, these ridges 23, 69 serving to prevent entry of undesirable substances to the supply reservoir and also serving to prevent undesirable 40 escape of oil from within.

The pump actuating or driving mechanism is common to all of the pump units and is ordinarily completely immersed within the oil 31 in the supply reservoir. The driving mechanism comprises a rotary horizontal 45 drive shaft 8 one end of which is mounted in a bearing 53 detachably associated with one side wall of the casing 2, and the opposite end portion of which projects outwardly beyond the opposite side wall of the 50 casing. The outwardly projecting end of the rotary shaft 8 is provided with a hand crank 68 whereby rotary motion may be imparted to the drive shaft for priming or 55 similar purposes. The portion of the drive shaft 8 adjacent to the crank 68 is embraced by a relatively rotatable sleeve 63 which penetrates the side wall of the casing 2 and is snugly embraced by a stuffing box 67 and packing 66 which provide a bearing and 60 prevent escape of oil along the outer surface of the sleeve 63. Leakage of oil through the interior of the sleeve 63 is likewise prevented by a stuffing box and packing coacting 65 with the sleeve 63 and shaft 8 adjacent

to the crank 68. The outer end of the sleeve 63 is provided with a rock arm 65, or a pulley, gearing, or other means adapted to impart either intermittent, oscillatory or continuous rotary motion to the sleeve 63. The inner end of the sleeve 63 is provided with a pawl carrier bracket 62 having a pawl 61 pivotally associated therewith, the pawl being engaged by a leaf spring 58. The pawl 61 normally engages the side teeth of a ratchet wheel 12 which is rigidly attached to the shaft 8 in any suitable manner, and which also has teeth around its periphery. A leaf spring 28 attached to the casing 2 by means of a screw 42, has a free end which 70 normally engages and is adapted to ride over the peripheral teeth of the ratchet wheel 12. With this arrangement of drive shaft 8, sleeve 63, carrier 62, pawl 61, ratchet wheel 12 and leaf springs 28, 58, it will be 75 obvious that either continuous or intermittent rotary motion may be transmitted from the sleeve 63 to the drive shaft 8 in one direction, and that the spring 28 will effectively prevent reverse rotation of the shaft 8. The portion of the shaft 8 between the sleeve 63 and bearing 53 is of hexagonal formation and carries a pair of laterally spaced pump actuating eccentrics 10 having hexagonal 80 openings closely fitting the hexagonal drive shaft portion. The eccentrics 10 are held in properly spaced relation by means of a ring spacer 64 surrounding the shaft 8. The eccentrics 10 are preferably spaced equidistant about the axis of the shaft 8, in order to uniformly distribute the driving forces. The eccentrics 10, sleeve 64 and ratchet wheel 12 are freely endwise removable from the hexagonal portion of the shaft 8, and the sleeve 63 is likewise removable from the 85 cylindrical portion of the shaft 8 when the crank 68 is removed. The shaft 8 and sleeve 63 may also be withdrawn endwise from within the casing 2 through the stuffing box 67 and packing 66. 90

Each of the independent pump units comprises a pair of similar parallel plungers 5, 11 of equal diameter associated with a common actuating head 27 which rests upon an adjacent actuating eccentric 10. The low pressure plunger 5 has a lost motion connection with the head 27, while the high pressure plunger 11 is rigidly attached to the head, the transverse pin 37 or a nut serving to permit limited movement of the low pressure plunger 5 relatively to the head 27. The plungers 5, 11 are simultaneously reciprocable within parallel vertical bores of the pump frame 3 which is detachably secured to the cover 22 and casing 2 by means of a removable discharge valve casing 20 and a removable set screw 21. The plungers 5, 11 are urged downwardly toward the actuating eccentric 10 by means of a single helical compression spring 39 surrounding 100

the high pressure plunger and cylinder, the lower end of the spring 39 coacting with the medial portion of the head 27 and the upper end reacting against the frame 3. The end 5 32 of the actuating head 27 remote from the plunger 5, is recessed to receive a pump stroke adjuster comprising a rod 9 adjustably supported by the frame 3 and having a lower end formed as an abutment 26 engageable with a lower surface of the end 32 to limit the downward movement of both of the plungers 5, 11. The upper end of the rod 9 is threaded and extends through a hole in the frame 3. An adjusting nut 25 coacts 10 with the threaded rod end and permits convenient adjustment of the pump stroke from the exterior of the casing 2 and cover 22. The rod 9 is forced downwardly to maintain contact between the nut 25 and the frame 3, by means of a helical compression spring 24 the lower end of which coacts with a collar rigidly attached to the rod 9 and the upper end of which reacts against the frame 3.

25 The low pressure plunger 5 of each pump unit, is adapted to withdraw oil 31 from the supply reservoir through a vertical suction pipe 4 secured to the frame 3 and through a conduit 40 formed within the frame 3.

30 The lower end of the suction pipe 4 carries an inlet valve casing 71 located near the bottom of the casing 2 and having an inlet opening protected by a strainer 30. A pair of ball inlet valves 14, 29 are arranged in series within the inlet valve casing 71. The low pressure plunger 5 of each pump unit is adapted to deliver oil 31 past a ball discharge valve 19 through a discharge conduit 38 formed in an overflow pipe 47 detachably secured to the frame 3, to a sight flow indicator.

40 The sight flow indicator for the low pressure pump discharge, comprises a downwardly directed tube 51 connecting the pipe 47 with a nozzle 46, a bracket 57 secured to the frame 3 below the nozzle 46 and provided with an annular upper recess 56 coaxial with the nozzle, and a transparent tube 7 fitted within the recess 56 and extending 45 upwardly above the nozzle 46. A cap 49 having a relatively large vent opening 50 surrounding the nozzle 46, engages the upper end of the tube 7 and is urged thereagainst by means of a coil spring 48. The opening 55 50 establishes atmospheric pressure in the conduits communicating with the low pressure pump discharge valve 19. The spring 48 is readily compressible to permit complete vertical withdrawal of the lower end 60 of the tube 7 from the recess 56, and subsequent lateral removal of the tube 7.

65 The high pressure plunger 11 of each pump unit is adapted to receive oil 31 from the sight flow indicator past a spring pressed spherical seated poppet valve 18 having

a seat in the bracket 57. The plunger 11 delivers oil past an initial ball discharge valve 17 into a conduit 43 which communicates with a passage 59 formed in the intermediate discharge valve casing 20. The 70 initial high pressure discharge valve 17 is spring pressed and is removable from the exterior of the casing 2 by virtue of the removable screw plug 36. The removable intermediate discharge valve casing 20 is 75 preferably provided with several passages 59 in order to insure proper communication with the passage 43. The intermediate discharge valve 16 is of the spring pressed ball type and controls the delivery of oil through the casing 20 to the final discharge valve 15. The final discharge valve 15 is mounted in a removable valve cage 35 detachably secured to an integral portion 33 of the casing 2, the valve 15 controlling delivery of 80 oil to the final discharge and distributing pipe 6. The discharge valves 15, 16 are readily removable and insertible with the aid of an ordinary wrench and screw driver.

85 Each of the final discharge pipes 6 is 90 rigidly attached to a portion 33 of the stationary casing 2 by means of an elbow 34 and a union 41. The pipes 6 communicate with any desired source of oil utilization. By attaching the pipes 6 directly to integral portions of the stationary casing 2 rather than to the pump frames 3 or the cover 22, the pumps and the various elements associated therewith, may be readily removed without interfering with the pipes 6.

95 During normal operation of the device, the supply reservoir is provided with an abundant supply of oil 31 and the elements are assembled as indicated. The main shaft 8 is then rotated, either continuously with the aid of gearing not shown, or by means of the intermittently oscillatory arm 65. As the low pressure plunger 5 moves downwardly under the influence of the single actuating spring 39, oil is drawn from the supply reservoir past the inlet valves 29, 14 through the suction pipe 4 and conduit 40 into the low pressure cylinder. As the high pressure plunger 11 moves downwardly simultaneously with the plunger 5 and under the influence of the same spring 39, oil at 110 atmospheric pressure is drawn from the sight flow indicator past the high pressure inlet valve 18 into the high pressure pump cylinder. The downward travel of the 115 plungers 5, 11 is limited by the abutment 26 of the stroke adjusting rod 9, movement of the pump plungers being arrested when the plunger head 27 engages the abutment 26.

120 As the driving eccentric continues to revolve after downward travel of the plungers 5, 11 has been arrested, it eventually reengages the stopped head 27 and simultaneously raises the plungers 5, 11 away from the abutment 26 compressing the single spring 130

39. As the low pressure plunger 5 moves upwardly, oil is forced past the low pressure discharge valve 19 through the passage 38, tube 51 and nozzle 46 into the sight flow 5 indicator preparatory to being withdrawn by the next suction stroke of the high pressure plunger 11. As the high pressure plunger 11 moves upwardly, oil is forced past the initial discharge valve 17 through the 10 passages 43, 59 and past the intermediate and final discharge valves 16, 15 respectively, into the final discharge pipe 6. Continued rotation of the drive shaft 8 causes the pump plungers 5, 11 to automatically 15 and intermittently withdraw batches of oil 31 from the supply reservoir and to deliver the oil to the final discharge pipe 6. The operation of each pump unit is the same, except that one unit of the group may be 20 engaged in a suction stroke while another unit is engaged in a discharge stroke, depending upon the angular setting of the eccentrics 10 relatively to the drive shaft 8.

The capacity of any pump unit may be 25 readily varied by manipulating the adjusting nut 25 to change the effective pumping stroke. The lost motion connection afforded by the pin 37 at the end of the low pressure plunger 5 is especially desirable when 30 operating with short stroke for light feeds. This lost motion connection permits relative movement of the plungers 5, 11 and prevents the low pressure plunger 5 from delivering an over supply of oil to the sight 35 flow indicator, such over supply being undesirable due to accumulation of excess oil in the gage glass 7. The sight flow tube 7 may be conveniently removed and replaced without interfering with the operation of 40 the pumps. The individual pump units may be quickly detached by merely removing the valve casing 20 and the retaining screw 21, which releases the unit for free vertical removal. The valves 15, 16, 17, 18, 45 19 are all readily removable and insertable from the exterior of the casing 2 and cover 22, and all of these valves except the valves 15 may be removed without interfering with the pressure in the discharge pipes 6. By 50 forming the plungers 5, 11 of equal diameter, the pump cylinders may be bored of equal diameters and the plungers may all be cut from the same diametered round stock. Such construction reduces to a minimum the 55 cost of manufacture. The use of a single spring 39 for urging both plungers in the same direction is possible because the low pressure plunger 5 is operating against atmospheric pressure. The various oil 60 passages may be readily formed by drilling thereby minimizing the entire cost of construction.

It should be understood that it is not desired to limit the invention to the exact details of construction and of operation herein 65 shown and described, for various modifications within the scope of the claims may occur to persons skilled in the art.

It is claimed and desired to secure by Letters Patent:—

1. In combination, high and low pressure pump plungers, a cross-head having its medial portion rigidly attached to said high pressure plunger and having one end portion operatively connected to said low pressure plunger through a lost motion connection, an adjustable stop cooperating with the opposite end portion of said cross-head for limiting the movement of said plungers in one direction, resilient means coacting 75 with one side of the medial portion of said cross-head for moving the same toward said stop, and means cooperating with the opposite side of the medial portion of said cross-head for moving the same in the opposite 80 direction.

2. In combination, high and low pressure pump plungers, a cross-head having its medial portion rigidly attached to said high pressure plunger and having an end portion 90 operatively connected to said low pressure plunger, an adjustable stop cooperating with an opposite end portion of said cross-head for limiting the movement of said plungers in one direction, a single spring surrounding 95 said high pressure plunger and coacting with the medial portion of said cross-head for moving the same toward said stop, and an eccentric cooperating with the medial portion of said cross-head for moving the 100 same away from said stop.

3. In combination, high and low pressure pump plungers having equal diameter, a cross-head having its medial portion rigidly attached to the lower end of said high pressure plunger and having one end portion operatively connected to the corresponding end of said low pressure plunger through a lost motion connection, an adjustable stop 105 cooperating with the opposite end portion of said cross-head for limiting the movement of said plungers in one direction, a single spring surrounding said high pressure plunger and coacting with one side of the medial portion of said cross-head to urge 110 said cross-head toward said stop, and a rotary eccentric cooperating with the opposite side of the medial portion of said cross-head to produce motion of translation thereof 115 away from said stop.

In testimony whereof, the signature of the inventor is affixed hereto.

EUGENE M. SCOVILLE.
